JAMES T. WALKER, OF ALBANY, NEW YORK.

Letters Patent No. 83,814, dated November 3, 1868.

IMPROVEMENT IN COLLAR-MACHINES.

The Schedule referred to in these Letters Patent and making part of the same.

To all whom it may concern:

Be it known that I, JAMES T. WALKER, of Albany, in the county of Albany, and State of New York, have invented a new and useful Machine for Making Collars and Cuffs; and I do hereby declare that the following is a full, clear, and exact description of the construction and operation of the same, reference being had to the accompanying drawings, making a part of this specification, in which—

Figures 1 and 2 are perspective views;

Figure 3 is a front elevation;

Figure 4 is a longitudinal section;

Figures 5, 6, 7, 8, 9, 10, and 11 are plane, side, and end views of the combination cutting-die and moulder, as adapted for cutting and moulding collars;

Figures 12, 13, 14, 15, 16, and 17 are similar views of the same, as adapted for cuffs;

Figures 18 and 19 are plane and sectional end views of the adjustable and vertically-reciprocating folding-blade or follower, adapted for use with the dies for making collars;

Figure 20 and 21 are similar views of the same, adapted to be used with the dies for cuffs; and

Figures 22 and 23 are plane views of the removable face-plate of the folder, adapted to be used respectively for collars or cuffs.

My invention consists of a machine so constructed and arranged as that it shall, by a continuous operation, produce a collar or cuff, finished for use, whether the same be made of paper, a compound fabric of muslin and paper, or from stiffened muslin; and also in so moulding and bending the collars or cuffs, by means of the peculiar shape of the dies, and the act of cutting them out, as that they shall fit the contour of the wrist or neck.

In order to enable others skilled in the art to make and use my invention, I will now proceed to describe its construction and operation.

The bed-plate A is placed and supported upon four legs, B B. On the upper side of the table thus formed are raised in suitable positions the two frames or supports, C C, for a walking-beam, D, and the two ways or guides E E, for a plunger, F. On the under side, also in suitable positions, are fixed the hangers G G, H H, and I; and there are also suitable apertures in the bed-plate for the purposes hereafter described.

The walking-beam D plays upon suitable bearings at a, and is operated by the crank-shaft M, which is provided as usual with belt-pulleys, turning in suitable bearings in the hangers G G, to which the shorter arm is connected by the rod N.

At the extremity of the short arm of the walking-beam D, and running through it and the rod N, at right angles to both, is a rod, O, which extends a short distance beyond each side of the bed-plate A. Attached to the long arm of the walking-beam D, by a short arm, P, which plays at both its extremities on the pivots b and c, and running between the two ways or guides E E, is the platen F.

Attached at right angles to the shaft M is the cam Q, and at a suitable point on the side of said cam is placed the stud R, which operates the levers V and W at suitable intervals, and causes the folding-blade to reciprocate vertically, as hereinafter more fully described.

At the side of the bed-plate A, attached to and revolving with the crank-shaft M, is the gear-wheel S, which meshes into and turns another gear-wheel, T, which revolves on the shaft U. Fixed in the hanger I, hung on the axis d and e, between the two hangers H H, are the two levers V and W, which are operated by the stud R and cam Q, which at each revolution of the crank-shaft M strike upon the curved short arms of both. The long arm of the lever W is joined by a short connection, X, to the short arm of the lever V by pivots f and g, upon which it moves, so that when the short arm of the lever W is depressed by the cam Q the long arm, by means of this connection X, forces up the short arm of the lever V, which has just been depressed by the stud R upon said cam.

To the long arm of the lever V, and at its extremity, is attached, by means of the pin h, upon which it plays, the adjustable folding-blade Y. This folding blade is suitably curved and shaped as that it shall assist in the folding and delivery of a collar, or so shaped that it shall deliver a cuff after the same is excised, as is shown in the detached views in figs. 18, 19, 20, and 21.

At the forward end of the bed-plate A, in front of the guides E E, is a folder, Z, which moves on an axis, i, which is fixed in two bearings raised from the bed-plate. This folder has two short arms, a', which extend below the bed-plate, and to which are attached the connecting-rods k k, by means of pivots b', their opposite ends being connected by pivots j j to the links l l, which play on two pivots, m m, fixed in the sides of the bed-plate, and to the rods n n, from which motion is received through the rod O, (to which they are connected, as will be more fully described,) attached to the walking-beam, which is operated by the main shaft. The upper ends of the rods n n are provided with slots o o through which pass the extremities of the rod O, the two small springs p p holding the rod O to duty at the upper ends of the slotted beams, except when the pressure from the short arm of the walking-beam D is directly downward.

Underneath the aperture K is situated a curved box, which is secured to the bed-plate in a proper position for the purpose of holding the paper, which is cut to the proper width and rolled on to a loose roller.

At the front of this box are fixed two small feeding-rollers, q and r, properly geared together, for delivering the paper to the dies, as required.

They are caused to revolve intermittently, or at each revolution of the main shaft, by the segment of gear s on the inside circumference of the cog-wheel T, which meshes into the small gear-wheel t at the extremity of the feed-roller r, whose axis extends, for that purpose, through its bearings on that side of the bed-plate A.

Extending from these feeding-rollers a suitable distance forward is a flat tube, u , the sides of which are adjustable towards the common centre by means of the thumb-screws v r . The box and feed-rollers are covered with a light cover, which protects the paper from all dust or dirt until it passes into the tube u , and from thence directly to the die.

The face-plate w of the folder Z is removable, and is provided with the slot or aperture X , through which the collar or cuff is drawn by the folding-blade or follower Y , said aperture being varied in form, to adapt it to the shape of the collar or cuff to be made, as shown in figs. 22 and 23.

The combination cutting-die and moulder is formed of three separate parts or pieces, A^2 , B^2 , and C^2 , different views of each of which are shown in the smaller figures, and is constructed as follows: The part A^2 , removable, and attached to the platen F , is a die formed in any required shape for a collar or cuff, on the face of which are raised small punches, suitably arranged for cutting the button-holes in either collar or cuff; and at a proper distance from the edge of the die is a row of raised teeth or projections, extending around the part corresponding to the portion of the collar or cuff upon which an imitation of stitching is desired.

The surface or cutting-face of this male die is so shaped as to slant downwardly and outwardly toward its sides, from a line drawn through its longitudinal diameter, as shown in the plane and end views, figs. 5 and 6, and 12 and 13, as that it shall fit upon a corresponding elevation of the face of the part C^2 of the female die, for the double purpose of bending and moulding the collar or cuff, or partially folding the same, and also of giving a shear-cut at the ends, as it descends through the counter-die B^2 , which is stationary, being so fixed to the bed-plate A as that one end of its upper surface is flush with that of the bed-plate, and its other end depressed or elevated, so that its surface shall lie in an inclined plane, for the purpose of insuring a shearing-cut upon the sides of the collar or cuff. The counter-die B^2 is provided with an aperture, shaped to correspond with the form of the die A^2 , in which said die shall closely fit, as it passes through to excise the collar or cuff.

The upper face of this counter-die may be bevelled its entire length, from one end to the other, as shown in side view, fig. 8, by which the shear-cut along the sides may be accomplished; and this latter mode of arranging the centre die, I prefer.

The follower of die C^2 of the counter-die B^2 is shaped to correspond with the male die A^2 , and rises and falls through the centre die B^2 , which is pierced to admit its passage, the parts fitting closely, and is elastically seated upon a spring, z , which, when in contact with the die A^2 , holds it up to duty, its upward motion being limited by suitable shoulders, as fully shown.

It is also slotted, to admit the passage of the folding-blade or follower Y , and also with apertures corresponding to the button-hole punches on the face of the die A^2 .

The operation of the machine is as follows: A roll of paper, cut to proper width, is placed in the box K , and its end introduced between the feeding-rollers q and r , and motion being communicated to the shaft M , and through it, by means of the gear-wheels S and T , to the segment of gear s , meshing into the gear-wheel t , causes the feeding-rollers q and r to revolve, and feeds forward the paper through the guide-tube u , a proper distance under the dies, and during which time the crank-shaft M , by means of the connecting-rod N , carries the short arm of the walking-beam D upward, and depresses its long arm with the platen F , and the die A^2 , which descends through the paper, and the aperture in the counter-die, and cuts the collar or

cuff out, at the same time forming and bending it by means of the peculiar construction of dies hereinbefore described, and punching the button-holes therein, and embossing the stitches thereon, the collar being creased to fold, by being forced upon the folding-blade Y , (then stationary,) by the continuous descent of the die A^2 , the bed C^2 being forced down upon its elastic seat.

The rotation of the main shaft being continued, the walking-beam lifts the platen F and die A^2 , leaving the collar or cuff cut, embossed, moulded, and creased on the face of the bed C^2 , and carries the rods n n downward and forward, imparting motion, through the rods k k , to the folder Z , carrying it down upon the counter-die, and over the follower C^2 , with the collar supported thereon, with its slot or aperture X directly over the aperture in the follower C^2 , within which is the folding-blade Y . The stud R , then striking the curved short arm of the lever V , causes its opposite end to rise, and forcing the knife or follower Y up through the slot or aperture in the counter-die, carries the collar up through the slot or aperture X in a doubled or folded condition. The cam Q then striking the curved short arm of the lever W , depresses it, and forces back the lever V and follower Y , into the position first occupied, and also causes the rod O , which, during the time the collar or cuff was being driven through the slot or aperture X , was moving upward in the slots o o , lifting the rods n n upward and backward, causing the rods k k to retract and lift the folder Z out of the way of the plunger F and die A^2 , allowing the collar to slide off into a proper receptacle, and the operation to be repeated, the crank-shaft having made a complete revolution, and all the parts of the machine being brought back into the position first occupied.

I have described my machine as adapted to the production of folded or turn-down collars.

It is obvious that by substituting dies of the shape of a cuff or garrote-collar, and shaping the die A^2 and follower C^2 to correspond therewith, and at the same time providing the follower C^2 and folder Z with apertures or openings of larger size, as shown in figs. 14, 15, 16, 22, and 23, and providing therefor a plunger or enlarged folding-blade, as seen in figs. 18 and 20, I am enabled to make either a cuff or collar which, while not being folded or doubled upon itself, is so shaped and moulded by the construction of the dies, as hereinbefore described, as that it shall perfectly fit the wrist or neck, and thus I am enabled to produce a finished article in one machine, without the necessity of moulding in a separate machine.

Having thus fully described my invention,

What I claim as new, and desire to secure by Letters Patent, is—

1. A collar or cuff-die, whose face is inclined downwards from its longitudinal centre, or point corresponding with the folding-line, substantially as herein specified.
2. The female die, or its movable bed, constructed to conform to the face of the male die, by being inclined downwards from the folding-line, substantially as set forth.
3. The female or counter-die B^2 , constructed as described, and arranged upon the bed A , with one end elevated above the other, presenting an inclined face, substantially as described.
4. In combination with the slotted follower C^2 , the knife Y , so arranged that it shall indent the collar upon its folding-line at each descent of the male die, substantially as and for the purposes set forth.
5. The slotted folder Z , in combination with the vertically-reciprocating knife Y , substantially as herein set forth.
6. Forming or bending the collar in the line of the fold,

as it is cut, in contradistinction to creasing the same, substantially as and for the purposes herein set forth.

7. A flat guide-tube, *u*, made adjustable, to suit the width of the paper, and arranged with the feeding-rollers *q* and *r*, for the purposes set forth.

8. The arrangement of the levers *V* and *W*, and cams *R* and *Q*, all constructed as shown, and operating to alternately cause the upward and downward motion

of the knife *Y*, substantially as shown and described.

9. A movable collar-shaped bed, *O²*, in combination with the dies *B²* and *A²*, substantially as and for the purposes set forth.

JAMES T. WALKER.
